STAND FOR DISPLAY AND PRESERVATION OF AUTOGRAPHED SPHERES SUCH AS BASEBALLS OR THE LIKE

William Wasilevich, New York, N. Y.

Application October 29, 1948, Serial No. 149,384

Term of patent 3½ years

(CL. D80—9)

To all whom it may concern:

Be it known that I, William Wasilevich, a citizen of the United States, residing at New York, in the county of New York and State of New York, have invented a new, original, and ornamental Design for a Stand for Display and Preservation of Autographed Spheres such as Base Balls or the like, of which the following is a specification, reference being had to the accompanying drawing, forming part thereof.

Figure 1 is a perspective view of a stand for display and preservation of autographed spheres such as base balls or the like, showing my new design.

I claim:

The ornamental design for a stand for display and preservation of autographed spheres such as baseballs or the like, as shown.

WILLIAM WASILEVICH.
